UNITED STATES PATENT OFFICE.

CARL J. MELLIN, OF RICHMOND, VIRGINIA.

SLIDE-VALVE.

SPECIFICATION forming part of Letters Patent No. 621,931, dated March 28, 1899.

Application filed April 23, 1898. Serial No. 678,574. (No model.)

To all whom it may concern:

Be it known that I, CARL J. MELLIN, a citizen of the United States, and a resident of Richmond, in the county of Henrico and State 5 of Virginia, have invented certain new and useful Improvements in Slide-Valves for Motor-Engines, of which the following is a specification.

My invention consists of an improvement 10 of the valve known as the "Allen" valve, whereby there is a double opening of exhaust when the valve begins to exhaust and for a short time thereafter same, as there is double opening for the admission of steam with said 15 valve as ordinarily constructed, and thus the cylinder is more effectively exhausted when the piston begins its stroke, which facilitates high speed, as hereinafter fully described, reference being made to the accompanying 20 drawings, in which—

Figure 1 is a sectional elevation of a flat D-valve and the port-face of the cylinder, showing the valve as moving to the right hand to exhaust the right-hand steam-port and admit steam to the left-hand port. Fig. 2 is a like section showing the valve at the point of opening the left-hand steam-port both at the left-hand end of the port and at the right-hand end of the Allen passage through the 25 valve. Fig. 3 is a like section showing the valve as returning to the left hand after the right-hand port has been exhausted to exhaust the left-hand port and admit steam to the right-hand port and showing one exhaust 30 opening directly into the exhaust-cavity of the valve and another exhaust through the Allen passage and the mouth of the previously-exhausted right-hand port into the exhaust-cavity; this being the operation due to 35 my improvement of the valve. Fig. 4 is a longitudinal sectional elevation of a half portion of a piston-valve, showing the application of the invention to such valves as well, with steam-inlets at ends of the valve and exhaust at the middle, same as the flat valve, the valve being in the middle position. Fig. 40 45 50

off in moving to the right; and Fig. 7 is a transverse section on line 22, Fig. 5.

A represents the slide-valve, having the ordinary Allen passage b from one face to the other over the exhaust-cavity d.

e and f represent the steam-ports, and g the exhaust-port, in the cylinder port-face h.

The function of the passage b is well understood, the same being, as before stated, to open double passage for the steam at the beginning of the inlet; but beyond this its operation is the same as any other slide-valve owing to the fact that as heretofore constructed the part of each valve-face c between the mouth of the passage b and the exhaust-cavity has been made as wide as or wider than the steam-port, so that the whole breadth of the steam-port is covered prior to or at the 60 moment of the opening of the exhaust. Now I construct this portion of the valve-face c narrower than the steam-port, whereby there is at and for some time after the direct opening of the exhaust at j another opening at k 65 into passage b, and thence through the mouth of the already-exhausted steam-port at the other end into the exhaust-cavity, as indicated by the arrow l, whereby there is double 70 opening of exhaust at the beginning, and there is also exhaust from in front of the piston just before it reaches the end of the stroke, which with all other slide-valves is cut off some time before the end of the stroke. Thus 75 with the adjustment of the valve to open the 80 exhaust a short time before the piston reaches the ends of its stroke there is complete discharge of steam at the beginning of the reverse movement of the piston.

In the piston-valve the application of the invention is practically the same with only such modifications of the valve and valve-case as the nature of the different form of valve requires. A' represents the valve. It has the same Allen passage b from one face c to another over the exhaust-cavity d. e and f represent the steam-ports, and g the exhaust-port, the steam being admitted at i to the ends of the valve, or the exhaust may be from the ends of the valve through i and be admitted through g.

I claim—

In a slide-valve having the passage b, from one to the other of the valve-faces c past the

exhaust-cavity, the parts of said faces *c*, between the mouths of said passage and the exhaust-cavity being of less breadth than the breadth of the steam-ports respectively, 5 whereby during the fore part of the opening of direct exhaust there is also exhaust through passage *b*, and the mouth of the opposite pre-

viously-exhausted steam-port substantially as described.

CARL J. MELLIN.
